[57] CLAIM

The ornamental design for an over the wing bridge for airports, as shown and described.

DESCRIPTION

FIG. 1 is a perspective view of an over the wing bridge for airports with the front portion lowered, showing my new design;

FIG. 2 is a left side elevation view with the front portion raised, the right side being a mirror image thereof; FIG. 3 is a left side elevational view with the front portion lowered, the right side being a mirror image thereof;

FIG. 4 is a top plan view thereof;

FIG. 5 is a bottom view thereof;

FIG. 6 is a rear elevational view thereof; and,

FIG. 7 is a front elevational view thereof.

FIG. 4

FIG. 3

FIG. 5

FIG. 7

FIG. 6
